UNITED STATES PATENT OFFICE.

ROBERT ATKINSON GARTSIDE AND DAVID GENESE, OF BALTIMORE,
MARYLAND.

HEATING-STOVE.

SPECIFICATION forming part of Letters Patent No. 404,273, dated May 28, 1889.

Application filed June 22, 1888. Serial No. 277,913. (No model.)

To all whom it may concern:

Be it known that we, ROBERT ATKINSON GARTSIDE and DAVID GENESE, citizens of the United States, residing at Baltimore, in the 5 State of Maryland, have invented new and useful Improvements in Heating-Stoves, of which the following is a specification.

This invention relates to that type of stoves known as "latrobes," and has for its object to 10 provide a novel construction whereby the waste of heat is in a large measure avoided and the cold air at or near the floor of an apartment is drawn into hot-air chambers or flues interposed between the stove-body and 15 the smoke-flues, to be there heated and discharged into the apartment, thus materially increasing the heating capacity and usefulness of the stove.

The object of our invention we accomplish 20 in the manner and by the construction and combination of devices hereinafter described and claimed, reference being made to the accompanying drawings, in which—

Figure 1 is a front elevation of a stove embodying our invention; Fig. 2, a horizontal sectional view on the line $x-x$, Fig. 1; Fig. 3, a detail plan view of the stove-base or ash-pit to show the flues therein; Fig. 4, a detail bottom plan view of the stove-body; and Fig. 5, a vertical sectional view on the line $y-y$, Fig. 1.

In order to enable those skilled in the art to make and use our invention, we will now describe the same in detail, referring to the drawings, wherein—

35 The numeral 1 indicates the stove-body, having the usual magazine, grate, and other appurtenances common to latrobes, and provided at each side with a vertical smoke-flue, 2, between which and the stove-body is located 40 a vertical air-heating chamber or flue, 4, the outer walls, 5, of which constitute the inner walls of the smoke-flues. The stove-body communicates with the smoke-flues by short lateral tubes or flues 3, that extend through the 45 air-heating chambers 4, and from the cap- plate 6, which closes the upper ends of the smoke-flues and air-heating chambers or flues, projects a thimble or flue, 7, that serves to connect a smoke-flue with the chimney for carrying off the products of combustion from the 50 stove-body. The smoke-flues and air-heating

chambers are open at their lower ends, and the outer sides of the said air-chambers 4 are provided at their top portions with lateral exit- 55 orifices 8, for the discharge of hot-air into the apartment or room.

The base of the stove is provided with suitable doors or dampers, as indicated in Fig. 1, and comprises a base-plate, 9, formed with curved partition-walls 10 and 12, that curve 60 from the front portion around to the rear to provide two curved cold-air flues, 13, which underlie the lower open ends of the air-heating chambers or flues 4. The base-plate 9 is also furnished with a marginal wall, 14, to provide a continuous flue, 15, which communicates with and connects the lower open ends of the smoke-flues 2.

The stove-body is surrounded in part by a casing or hood, 16, covering the rearward and 70 lateral portions thereof, but so arranged in relation to the stove as to provide ample space for air-circulation, said casing or hood extending down to the floor in rear of and in contact with the marginal wall 14 of the base-plate 9 75 and provided with a central rear cold-air-supply flue, 17, by which air is led from a cellar to the space between the hood and stove, where such air is heated, and then rises and passes out at the front into the apartment or room. 80

The cold air at or adjacent to the floor of the apartment or room enters the front ends of the base-flues 13, passes upward into the chambers or flues 4, where it is heated, and then discharges through the exit-orifices 8 into the 85 apartment or room.

The air-heating chambers are curved in cross-section and elongated around the stove-body, and their forward walls, which have the hot-air exits 8, are exposed at the front of the 90 stove. As the outer walls of the air-chambers constitute the inner walls of the smoke-flues, the latter serve in a large measure to heat the air which enters the air-chambers through the horizontal cold-air flues 13 in the base of the 95 stove.

The doors 18 of the stove are provided with mica panes 19, having minute perforations 20 in the upper portions for the purpose of admitting air, which combines with the gases 100 above the actual zone of combustion, thereby supplying oxygen and effecting a more com-

plete combustion of the gases. In this improved stove the heat evolved is utilized to heat the air-chambers in contradistinction to such heat being expended on the smoke-flues, 5 while a continuous supply of fresh warm air enters the apartment.

Having thus described our invention, what we claim is—

10 The combination, with a latrobe-stove, of the smoke-flues connected with the stove-body, the air-heating chambers interposed between the smoke-flues and the stove-body and having hot-air-exit orifices in their upper portions, a thimble or flue for conducting the products

of combustion to a chimney, the stove-base 15 having a continuous flue communicating with the smoke-flues and air-inlet flues communicating with the air-heating chambers, and a casing or hood partially surrounding the stove and having an air-supply flue, substantially 20 as described.

In testimony whereof we affix our signatures in presence of two witnesses.

ROBERT ATKINSON GARTSIDE.
DAVID GENESE.
